UNITED STATES PATENT OFFICE

HENRY CAVE, OF HARTFORD, AND CURTISS F. SMITH, OF WEST HARTFORD, CONNECTICUT, ASSIGNORS TO THE FULLER BRUSH COMPANY, OF HARTFORD, CONNECTICUT, A CORPORATION OF CONNECTICUT

CLEANING TOOL

Application filed September 23, 1927. Serial No. 221,575.

Our invention relates to the class of tools more especially designed for cleaning windows and similar surfaces, where water is employed in a part of the operation, and 5 an object of the invention, among others, is the provision of a tool of this class by means of which the entire operation of washing and drying the cleaned surface may be efficiently and quickly performed.

10 One form of tool embodying our invention and in the construction and use of which the objects herein set out, as well as others, may be attained, is illustrated in the accompanying drawings, in which—
15 Figure 1 is a side view of our improved cleaning tool.

Figure 2 is a view in central crosswise section through the tool.

Figure 3 is a top view.
20 Figure 4 is a view showing the parts disassembled but approximately in their relative positions.

Figure 5 is a detail sectional view, scale enlarged, showing the means for connecting 25 the handle to the brush frame.

This improved cleaning tool embodies in a single structure two members commonly employed for washing windows and similar surfaces, the members being so arranged that 30 either may be used independently of the other for accomplishing a purpose. It will, however, be understood that while the invention contemplates means for readily securing the wiper to the tool, yet the invention is also present in the structure irrespective of the wiper.

In the accompanying drawings the numeral 5 indicates the frame of a brush that 40 may be formed in any suitable manner to receive and secure the bristles 6, in the structure herein shown a brush strip comprising this frame being of U-shape in cross section and within the trough of which the bristles 45 or other brush material are or is clamped between the sides of the trough shaped strip. This frame preferably has parallel sides joined by rounded ends and it is made from a single strip bent to shape and having the 50 meeting ends between clamp plates 7—8 and

at about midway between the ends, as shown in Figure 2 of the drawings.

The lower clamp plate 7 has oppositely arranged flanges 9 and the upper clamp plate 8 has grooves 10 at opposite sides terminating in flanges 11, the distance between adjacent flanges 9 and 11 on the lower and upper clamp plates being sufficient to receive sides 12 of the frame, said sides being located in the grooves 10 and held therein by the plate 7. It will be noted by inspecting Figs. 4 and 5 that the middle portion of the plate 7, that is the portion extending longitudinally between the flanges 9, is arched or bowed transversely so that when this middle portion of the plate 7 is drawn toward the plate 8 by the screw 14 and its cooperating nut, the flanges 9 will be moved away from each other, such movement causing the flanges to clamp the sides 12 of the frame in the grooves 10. Holes 13 are formed through the clamp plates in position to register with each other and thereby constitute in effect a single hole. This is preferably square to receive the squared portion of a clamp bolt 14 adjacent to the head, a nut 15 being employed to secure the two plates together.

75 A socket 16 is formed to receive a handle 17, and this socket has a foot 18 particularly formed to fit and be secured to the clamp plates. To this end the foot is flattened and has a notch 19 through which the bolt 14 passes, and flanges 20 are formed on opposite sides of the foot with notches 21—22 spaced apart to receive ribs 23 on the clamp plate 8 and within which the grooves 10 are formed. A thumb nut 24 fitting the bolt 14 serves to secure the foot 18 and thereby the socket 16 to the structure.

80 The shank 25 of a wiper 26 is also adapted to be secured to the structure hereinbefore described, this shank being of trough shape comprising flanges 27 and a bottom 28, the latter having a notch 29 within which the bolt 14 is received and the bottom also is provided with grooves 30—31 to fit over the ribs 23.

85 The outer end of the wiper may be of any desired form and construction and when 90 95 100

secured in place it is interposed between the foot 18 and the clamp plate 8, as illustrated in Figure 4, and in this case the notches 21—22 on the foot 18 fit over the ribs 32—33 within which the grooves 30—31 are formed, the thumb nut thus securing the wiper and the socket securely in place.

In accordance with the provisions of the patent statutes we have described the principles of operation of our invention, together with the device which we now consider to represent the best embodiment thereof, but we desire to have it understood that the device shown is only illustrative and that the invention may be carried out by other means and applied to uses other than those above set out.

We claim—

1. A cleaning tool comprising a brush including a frame, clamp plates oppositely located one with respect to the other, one plate having open ended grooves at opposite sides to receive opposite sides of said frame and the other plate being located in engagement with the first plate between said grooves to clamp opposite sides of said frame, and means for securing said plates to effect said clamping.

2. A cleaning tool comprising a brush including a frame, clamping plates, one having a rib with a groove therein on the under side to receive said frame and the other plate being located to clamp said frame within said groove, a handle member having a portion to rest against said plate and a notch within which said rib is received, and means for securing said plates together and said handle to said plates.

3. A cleaning tool comprising a brush including a frame having oppositely located sides, clamp plates, one plate having ribs containing oppositely disposed grooves to receive said sides and the other plate being secured to clamp said sides within said grooves, a handle having notches to fit said ribs, and means for securing said handle to said plates.

4. A cleaning tool comprising a frame, clamp plates secured to said frame and having ribs, a wiper including a shank having grooves within which said ribs are received, a handle member to overlie said shank, and means for drawing said plates and said handle member together to clamp said wiper shank against said rib.

5. A cleaning tool comprising a frame, clamp plates secured to said frame and having ribs, a wiper including a shank having ribs containing grooves within the latter of which the ribs on the clamp plates are received, a handle member having grooves within which the ribs on the wiper shank are received, and means for drawing said clamp plates and handle member together to clamp the handle member to the ribs of the

wiper shank and the latter to the ribs of the clamp plates.

6. A cleaning tool comprising a plate having spaced ribs, an implement carrying shank having grooves formed to receive the plate ribs, a handle having a foot to engage said shank, and means for drawing together the handle foot and the plate to clamp the shank against said plate ribs.

7. A cleaning tool comprising a plate having spaced ribs, an implement carrying shank having ribs spaced to correspond with the ribs on the said plate and having grooves formed in the reverse side of the said ribs to receive the plate ribs, a handle having a foot formed with grooves to receive the ribs on said shank, and means for drawing together said foot and plate to clamp said shank therebetween.

8. A cleaning tool comprising a brush frame having spaced sides, a plate having grooves to receive said frame sides, a second plate having portions to engage said frame sides opposite said grooves and an arched portion therebetween, and means for applying pressure against said arched portion tending to straighten out the same for moving the frame engaging portions nearer said grooves to clamp said frame sides therein.

9. A cleaning tool comprising a brush frame having spaced sides, clamping plates having their edges shaped to cooperatively form frame side receiving grooves and with each groove having opposed flanges, and means for moving said opposed flanges laterally one toward another to hold the frame sides in said grooves.

10. A cleaning tool comprising a brush frame having spaced sides, clamping plates having their edges shaped to cooperatively form frame side receiving grooves and with each groove having opposed flanges, means for moving said opposed flanges laterally one toward another to hold the frame sides in said grooves, and a handle attached to said plates and detachable therefrom without releasing said brush frame.

11. A cleaning tool comprising a brush including an open frame formed of a single strip having its ends arranged in line one with the other, opposed clamp plates bridging the joint between said ends and gripping them and also the frame at a point removed from said ends, the remainder of the frame to the ends thereof projecting in opposite directions from said clamp plates, and means for connecting said plates.

12. A cleaning tool comprising a plate having parallel ribs and an aperture located between said ribs, an implement carrying shank having grooves formed to receive the plate ribs and a notch to register with the aperture, a handle having a foot engaging said shank and a notch to register with said aperture and a shank notch, and means pass-

ing through said aperture and notches for drawing together the handle foot and the plate to clamp the shank against said plate ribs.

5 13. A cleaning tool comprising a plate having a rib, an implement carrying shank having a groove formed to receive the plate rib, a handle having a foot to engage said shank, and means for drawing together the handle foot and the plate to clamp the shank against said plate rib.

10 14. A cleaning tool comprising a plate having a rib, an implement carrying shank having a rib positioned to correspond with the rib on said plate and having a groove formed in the reverse side of said rib to receive the plate rib, a handle having a foot formed with a groove to receive the rib on said shank, and means for drawing together 15 said foot and plate to clamp said shank therebetween.

15 15. A cleaning tool comprising an implement holding device having spaced ribs, a handle having a foot to engage said device, 20 said foot including a flat portion having side flanges formed with notches to receive the spaced ribs, and means for drawing together the device and the foot to connect the implement to the handle.

25 16. A cleaning tool comprising a frame, 30 clamping plates secured to said frame and having ribs, a wiper including a shank having a plurality of transverse abutments to engage certain sides of said ribs, a handle 35 member to overlie said shank, and means for drawing said plates and said handle member together to clamp said wiper shank against said ribs.
